MECHANICAL MOVEMENT

William S. Taylor, Jr., Salt Lake City, Utah

Application September 5, 1939, Serial No. 293,520

3 Claims. (Cl. 74—57)

This invention relates to a mechanism for converting reciprocating motion into rotary motion or rotary motion into reciprocating motion and is particularly directed to a device for rotating a shaft by power derived from an engine of the type having two or more reciprocating pistons.

A large number of devices have been proposed for the purpose of converting reciprocating motion into rotary motion and the reverse which employ a follower attached to a reciprocating element and guided in a spiral path about a cylindrical element keyed to a shaft. Noteworthy among such mechanisms is that described in my prior Patent No. 924,509 employing a continuous double spiral groove about the periphery of a cylinder. Engines utilizing this principle have a number of advantages as compared to engines employing the conventional crank-type drive. By an examination of the vector forces applied by a crank actuated by a reciprocating piston rod, it will be at once apparent that the full power developed by the system is not applied to the rotating member except over a relatively few degrees intermediate the two dead centers. Further, in addition to applying full power over practically the entire extent of the stroke, an engine of the present type has fewer dead centers, each extending over a relatively short arc, for each stroke of the reciprocating member.

Heretofore a number of difficulties encountered in engines employing a drive mechanism of the present type, has prevented the practical application of such drives. I have found that these difficulties may be overcome by a proper balance of the various members making up the mechanism, by using a specially designed traveler and by providing a groove in the form of a double spiral groove about the periphery of the rotor, said groove being peculiarly adapted to cooperate with said follower to obtain maximum efficiency.

In order to achieve suitable balance it is necessary that an even number of travelers, each driven by either one or two cylinders, be employed and that said travelers be so positioned with respect to each other that the forces applied thereby to the rotor by each traveler, except for that component of force which drives the rotor in the desired direction, shall be equal and opposite in nature to forces applied to the rotor by at least one other traveler. It is desired that one traveler shall pass the point of dead center at one end of the rotor while the other traveler is passing the point of dead center at the other end

of the rotor. This requires that the dead centers shall be on opposite sides of the rotor axis and that the travelers shall be angularly spaced 180° apart with respect to the rotor axis. By this means, not only are the stresses incident to the passage of a traveler through the dead center equalized, but also the longitudinal thrust applied to the rotor by either traveler is canceled by an equal and opposite thrust applied to the rotor by the opposing traveler.

The novel and useful features of the improved rotor and traveler of this invention cooperate with each other and with the relative placing of the travelers to provide an engine drive which operates very smoothly and furnishes full power available from each of the cylinders except during the small fraction of the rotation of the shaft required for the corresponding traveler to pass the point on dead center.

Particular design and arrangement of parts by means of which these results are obtained as well as other objects and advantages of the present invention than those set forth above will be apparent from the following discussion of a preferred embodiment thereof when considered in connection with the attached drawings where-
in:

Figure 1 is a longitudinal sectional view taken at an angle of 45° to the vertical (on line 1—1 of Figure 2) through an engine embodying the novel features of this invention;

Figure 2 presents a vertical section on line 2—2 of Figure 1;

Figure 3 illustrates a view of the engine shown in Figure 1 with the cover plate of a guide way for one of the travelers removed;

Figure 4 is a diagrammatic presentation of the rotor and travelers taken at right angles to the showing of Figure 1; and

Figure 5 is a detail view of a traveler in perspective, showing the novel configuration thereof in accordance with the present invention.

With particular reference to Fig. 1, it will be seen that the mechanism of this invention comprises a rotor 10 keyed to a shaft 11, which shaft 45 is mounted in a housing 12 by means of anti-friction bearings 13 and thrust bearings 14. If desired a fly wheel (not shown) may be mounted on the shaft 11. A suitable lubricating oil inlet 15 and convenient outlets 16 are provided in the housing 12 in order that the mechanism may be operated in a bath of lubricant.

About the periphery of rotor 10, a groove 17 is cut in the form of a continuous double spiral having the opposite ends thereof axially dis- 55

posed 180° apart with respect to the rotor axis. The groove is of constant depth and the width thereof is constant throughout its length except at the said ends where it is substantially widened 5 for a purpose to be hereinafter set forth.

An even number of travelers, each comprising a head 18 and a shaft 19, are disposed about the rotor in pairs in such manner that the head 18 lies substantially within the groove 17. The heads of 10 the two travelers in each pair are disposed within the groove 17 on directly opposite sides of the axis of the rotor 10. By this means the longitudinal stress of each of the travelers is canceled by an equal and opposite longitudinal thrust applied 15 through the rotor 10 by the other member of the pair, in accordance with the theory set out above.

Means are provided to operatively connect each of the shafts 19 to a reciprocating member, or 20 pair of reciprocating members, outside the housing 12. In the embodiment here shown, each of the travelers is connected by means of a piston rod 20 to the piston of a reciprocating engine (not shown) at each end of the device. In 25 the specific mechanism shown, employing four travelers, there will preferably be eight cylinders, four at each end disposed parallel to the shaft 11 and arranged at angular intervals of 90° about said shaft 11. The termination of each of the 30 piston rods 20 adjacent a traveler shaft 19 is provided with a flange 21 adapted to cooperate with a similar flange on the opposing piston rod 20 to secure said piston rods to a cross-head 22. Bolts 23 are passed through openings in each 35 of the flanges 21 and through an opening in the cross-head 22. Nuts 24 on the ends of said bolts secure the entire assembly in proper relationship. Each of the cross-heads 22 is preferably lined 40 with a bearing metal 25 in a cylindrical bore thereof to receive the shaft 19 of the traveler in a manner to reduce friction to a minimum.

The traveler is positioned in the cross-head 22 for rotation with respect thereto by means of washers 26 and 27 and a nut 28 on the threaded 45 end of shaft 19 opposite the traveler head 18. It will be noted that washer 26 may function as a shim to regulate the clearance between the bottom of groove 17 and the traveler head 18.

Guideways for the cross-heads 22 are provided by cooperation between walls 29 of the 50 housing 12 having shoulders 30 and shoulders 32 of a cover plate 31. The cover plate 31 is secured to the housing by bolts 33 engaging threads tapped in wall 29.

It will be seen that this arrangement and combination of parts provides positive guideways for the cross-head 22 while permitting ready inspection and replacement of parts. Ease of assembly and means for inspection and replacement of the 60 rotor are provided by forming the housing 12 with one open end adapted to be closed by a cover plate 34 secured to the housing 12 by bolts 35.

In order to reduce the number of dead centers it is preferred that the double spiral groove 65 17 shall pass at least one and one-half times about the rotor 10 in progressing from one end of said rotor to the other end. By this means one cycle of the piston rods 20 causes three revolutions of the rotor 10 while the traveler head 18 passes through two dead centers. In comparison 70 a crank-type drive passes through six points of dead center for the same number of revolutions. In order to insure that the traveler head 18 passes the crossing points of the two oppositely 75 directed spirals of the groove 17 in proper man-

ner, the said head 18 must be of a length at least equal to twice the width of the groove 17, preferably at least three times the width of said groove. The edges at the ends of the head 18 are tapered in the manner shown and the upper 8 corners of said edges are rounded off as may be seen in Fig. 5.

Using a traveler of the type described it is necessary that those points in the groove where the helical pitch is varied, adjacent the dead centers, 10 be widened to a substantial extent in order to provide room for the traveler to pass through the point of dead center. Such a construction is shown in Fig. 4.

It will be apparent to those skilled in the art 15 that the present device is capable of efficient operation to convert rotary motion into reciprocating motion by applying power to shaft 11 in order that rotor 10 becomes the driving member and the rods 20 become driven members through the 20 medium of groove 17, the traveler and cross-head 22.

I claim:

1. In a device of the class described, a frame member, a cylindrical rotor mounted for rotation in said frame member having a continuous double spiral groove about the periphery thereof consisting of a right hand spiral and a left hand spiral joined at their ends, each spiral of said groove making at least one and one-half turns 30 about said rotor and having its opposite ends on opposite sides of the axis of said rotor, whereby each of said spirals crosses the other of said spirals at least twice, those portions of the groove at each end of the rotor where the two spirals 35 are joined being of constantly varying helical pitch to provide a smooth turn in the groove and being substantially wider than the remainder of the groove, an even number of traveler elements positioned in said groove in pairs, a number of 40 reciprocating elements equal to the number of said traveler elements mounted for reciprocation in said frame parallel to the axis of said rotor, said reciprocating elements being mounted in pairs, the two elements of each of said pairs 45 being on opposite sides of the axis of said rotor, independent means to supply power to each of said reciprocating elements, and means operatively connecting each of said travelers to one of said reciprocating elements permitting rotary 50 motion of said traveler with respect to said reciprocating element about an axis lying substantially in a line which is a diameter of said rotor.

2. In a device of the class described, a frame member, a cylindrical rotor mounted for rotation in said frame member having a continuous double spiral groove about the periphery thereof consisting of a right hand spiral and a left hand spiral joined at their ends, each spiral of said groove making at least one and one-half turns 60 about said rotor and having its opposite ends on opposite sides of the axis of said rotor, whereby each of said spirals crosses the other of said spirals at least twice, those portions of the groove at each end of the rotor where the two spirals 65 are joined being of constantly varying helical pitch to provide a smooth turn in the groove and being substantially wider than the remainder of the groove, an even number of traveler elements positioned in said groove in pairs, a number of 70 reciprocating elements equal to the number of said traveler elements mounted for reciprocation in said frame parallel to the axis of said rotor, said reciprocating elements being mounted in pairs, the two elements of each of said pairs 75

being on opposite sides of the axis of said rotor, means for operatively connecting each of said travelers to one of said reciprocating elements permitting rotary motion of said traveler with respect to said reciprocating element about an axis lying substantially in a line which is a diameter of said rotor, and independent power means associated with each of said reciprocating elements to cause reciprocation thereof, each of said traveler elements comprising a head of a length equal to at least twice its width and having a concave face, the longitudinal sides of said head normal to said face being substantially straight and parallel throughout the greater portion of the length thereof and tapering inwardly at the ends, the corners of said head remote from said face at the respective ends of said head being rounded.

3. In a device of the class described, a frame member, a cylindrical rotor mounted for rotation in said frame member having a continuous double spiral groove about the periphery thereof consisting of a right hand spiral and a left hand spiral joined at their ends, each spiral of said groove making at least $1\frac{1}{2}$ turns about said rotor and having its opposite ends on opposite sides of

the axis of said rotor, whereby each of said spirals crosses the other of said spirals at least twice, those portions of the groove at each end of the rotor where the two spirals are joined being of constantly varying helical pitch to provide a smooth turn in the groove and being substantially wider than the remainder of the groove, an even number of traveler elements positioned in said groove in pairs, a number of reciprocating elements equal to the number of said traveler elements mounted for reciprocation in said frame parallel to the axis of said rotor, said reciprocating elements being mounted in pairs, the two elements of each of said pairs being on opposite sides of the axis of said rotor, means operatively connecting each of said travelers to one of said reciprocating elements permitting rotary motion of said traveler with respect to said reciprocating element about an axis lying substantially in a line which is a diameter of said rotor, and means to supply power to each of said reciprocating elements on each side of said means operatively connecting said traveler to said reciprocating element.
